MEANS FOR DYEING FABRICS

Edward W. Smith, Melrose Highlands, Mass., assignor to
L. S. Adams Engineering Company, Boston, Mass.

Application March 17, 1954, Serial No. 416,850

12 Claims (Cl. 68—99)

The present invention relates to a means for dyeing fabrics in the open width, and more particularly to a means for dyeing fabrics which utilizes vibrational energy.

It is an object of the present invention to provide a means whereby the open fabric while immersed in a dye bath is subject to high frequency squeezing in such a way as to force the dye in and out of the fabric material.

Another object of the present invention is to provide a means for dyeing open width fabric by high frequency squeezing on a continuous basis in which the fabric is drawn continuously through the dye vat.

Another object of the present invention is to provide adjustable means for controlling the particular amount of pressure provided to squeeze the fabric, which pressure may be adjusted to the best value for the particular goods being handled.

In this invention, there is provided a dye vat for containing the dye liquor with a torsionally operated roll journaled in the vat at a position normally below the level of the liquor. About this roll are positioned a series of parallel pressure rollers designed to press the fabric against the torsionally operating roll as the torsionally operating roll moves the fabric through the liquor with an oscillating motion.

This construction and other objects and advantages of the present invention will be more fully understood when considered in connection with the drawings, in which:

Figure 1 shows a somewhat schematic side sectional elevation of the device.

Figure 2 shows a fragmentary sectional elevation of a detail including the torsionally operating roll taken from the opposite side of Figure 1.

Figure 3 shows a somewhat schematic end view taken along lines 3—3 of Figure 1.

Figure 4 shows a sectional view of a modification, and

Figure 5 is a fragmentary perspective detail of a portion of the modification shown in Figure 4.

An enclosed tank 1, preferably of stainless steel such as is commonly used in the textile industry, is provided for containing the dye liquor. The roller 2 having flanged ends 3 and 4 is positioned at the bottom of this tank at a level which will normally be lower than the level of the liquor (see Figure 2). This roller 2 is preferably formed of a hollow steel tube or pipe and is secured at its flanged ends 3 and 4 to the flanges 5 and 6 respectively of the shafts 7 and 8. The flanges 3 and 5, and 4 and 6 which are in face to face relation, may be secured together by welding or other suitable means. The axial elements 7 and 8 pass through the packing glands 11 and 12 in the opposite end walls 10 and 11, respectively of the tank 1. These packing glands (see Figure 2) are formed of annular rings 13 having a flanged section 14 extending outwardly from the shafts 7 and 8. These annular rings 13 are provided with annular gaskets 15 which form water tight fittings about the elements 7 and 8, while still permitting them to be freely rotated. Each annular ring 13 is secured to the wall of the tank by nuts and bolts 16 with the bolts passing

2

through the flange 14, the wall of the tank, and another annular ring 17 on the other side of the wall. If desired, a gasket 18 may be provided between the ring 17 and the wall 10.

It will be noted that these packing gland constructions also serve as bearings for the shafts 7 and 8. However separate bearing members may if desired be mounted outside of the tank to support the roller 2.

The shaft 8 is secured to and operated by a torsionally oscillating drive such as is shown in United States Patent No. 2,604,503, so as to insure the controllable torsional oscillation of the roll 2. The axle 20 of this drive element has a projecting end 21 suitably secured to it and extending into the open tubular end of the hollow shaft 8 (see Figure 2). This shaft 8 is secured to the member 21 by means of a clamping ring 22 with a series of adjustable radial bolts 23 passing through it. A sleeve and collar 24 and 25 respectively are also provided about the axle 20 of the drive element and serve to aid in securing the shaft

20 8 to the drive member 21.

A series of pressure rollers 26 (see Figure 3) preferably four in number, as illustrated, are arranged symmetrically about, and parallel to, the roller 2. Preferably two rollers 26 are positioned above and two rollers are positioned below the axis of shaft 2. These pressure rollers 26 are supported at each end on shafts 27 the ends of which fit into and are freely rotatable in bearings mounted in blocks 28. These blocks are supported in turn by a lever linkage system which when operated will simultaneously move 30 pairs of pressure rollers 26 toward or away from the roller 2. In this construction each of the blocks 28 in which the upper two rollers 26 are mounted are in turn secured one each to one end of the short levers 29. Each lever 29 is pivotally secured to the wall of the tank by a pin 30.

35 The other end 31 of these levers are each pivotally connected to a rod 32. Also pivotally connected to the lower end of each rod 32 is one end of an L-shaped lever 33 which is in turn pivotally supported on the wall of the tank by a pin 34. The other end of each of these L-shaped levers is secured to one of the blocks 28 supporting one end of one of the lower pair of rollers 26. At the upper end of the rods 32 are fixed operating arms 35 which extend out of the tank through bearing elements 36. An expansion spring 37 is positioned concentric with the end of each of these arms 35 between the bearing element 36 and a securing or adjustable nut 38. Thus in the operation of this device, the four rollers 26 as shown here may be adjusted so that they will press against the roller 2 with uniform pressure.

40 When the operating arms 35 are moved outwardly of the tank, the rollers 26 will move towards the roller 2 and when the arms 35 are moved further into the tank, the pressure rollers 26 will move away from the roller 2, thus reducing the pressure between them and the roller 2.

45 A pair of guide rollers 39 and 40 are journaled parallel to the roller 2 in the upper half of the tank and act as guide rollers around which the fabric material 41 being dyed may be guided and tensioned.

50 In the operation of this device, the fabric lengths 41 enter the tank in a continuous fashion passing beneath the roller 39 and between the roller 2 and the pressure rollers 26 and then around the guide roller 40 and out of the tank. All of these rollers except rollers 39 and 40 are below the level of the liquor. Roller 2 draws the fabric through the liquor by its rotation with a simultaneous torsional oscillation. The angular amplitude of the frequency of the oscillation of this roller is somewhat a matter of design, but in view of the universally available 60 cycles alternating current, it has been found most convenient to design and operate the torsionally resonant vibrating system at 120 cycles per second. It will be noted that the magnetic cir-

cuit of the torsionally operating drive shown in United States Patent No. 2,604,503 can readily give this number of pulsations per second to this system when operated from a 60 cycle current.

The angular amplitude on the surface of a six inch diameter roller may readily be made .15 inch through which amplitude the roller would oscillate 120 times per second. Assuming that a machine is designed to operate at the stated amplitude and frequency and further that the fabric length was moving through the machine at a rate of 15 yards per minute, or nine inches a second, which corresponds to a forward motion of .075 inch, during a complete cycle of vibration of roller 2 then the fabric would be subjected to four squeezes during the time it is passing between one of the pressure rollers and roller 2. As this device utilizes four pressure rollers, each section of the fabric would be squeezed ten times while submerged in the liquor. Such treatment very effectively brings the dye into intimate contact with the individual fibers and assists them in taking up the desired quantity of dye especially in cases where ready absorption of the dye would not ordinarily take place.

If it is found desirable to give a greater number of squeezes to the fabric than indicated above during the passage of the fabric through the machine, this may readily be done by slowing the speed of the fabric through the machine, by using a greater number of pressure rollers, or by increasing the stroke of the oscillating roll at its surface.

In the arrangement shown in Figures 4 and 5, the oscillating vibrating rotating roll 2, mounted in the tank 1 immersed in the liquid of the tank, has bearing against it four squeeze rolls 26', two on either side of the roll 2. These rolls 26' are journalled on shafts 46, 46, on the left of roll 2, and 47, 47 on the right of roll 2, supported by suspending bars 42 for the shafts 46, 46 and 43 for the shafts 47, 47. The bars 42 and 43 are pivoted at the top of the tank in blocks 48 and 49 which are adjustable horizontally between plates 58 and 59 by screws 60 and 61 which secure the block 48 and 49 in place.

These rolls 26' are held to the roll 2 by links 50 and 51 pivoted to bars 42 and 43 at points 44 and 45 between the places of journalling of shafts 46, 46, and 47, 47, on the bars 42 and 43. The links 50 and 51 are connected at their other ends to the cable 52 which passes over pulley 53 and is operated by lever 55.

The arrangement shown in Figure 4 is at each end of the tank and is operated by the arrangement shown in Figure 5. Here the lever 55, has an operating spring connection 56 connected to the pivoted arm 57' pivoted on the shaft 54 extending lengthwise of the tank. Within the tank the shaft 54 carries a crank arm 57 to the end of which is attached the cable 52 so that when the arm 55 in Figure 5 is rotated clockwise, the end of crank 57 is raised and the arms 50 and 51 are lowered, thus relieving to some extent, the pressure of the rolls 26' against the roll 2. When the arm 55 is moved counter-clockwise as viewed in Figure 4, the rolls 26' are drawn closed to the roll 2 and the fabric passing between the rolls 26 and 2 is squeezed to a greater degree. Lever 55 which may be suitably pivotally secured to the end tank wall is provided with a pawl 100 adapted to successively engage the saw teeth 101 which thereby hold the lever 55 in selected positions.

As the torsional oscillation of roller 2 is very rapid, as has been indicated above, it will usually be found helpful to have the surface of this roller somewhat roughened. This may be accomplished by sand blasting if a metallic surface for the roller is found necessary, or by covering the roller with a rubber or similar material which may be roughened to grip the goods and prevent the roll from slipping with respect to it, or by other suitable means.

Having now described my invention, I claim:

1. A means for dyeing fabric in the open width, comprising a tank adapted to contain dye liquor, a roll hori-

zontally journalled within and spaced from the walls of said tank, means for simultaneously rotating and torsionally vibrating said roll, at least one additional rotatable roll parallel to said first mentioned roll and means for pressing said additional rotatable roll and said first mentioned roll into contact with one another.

2. A means for dyeing fabric in a continuous process comprising a tank adapted to contain dye liquor, a rotatable roll horizontally journalled in said tank, means for guiding fabric lengths about said roll, means for simultaneously rotating and torsionally vibrating said roll, at least one rotatable pressure roll, and means supporting said pressure roll in parallel tangential pressured contact with said first mentioned roll.

3. A means for dyeing fabrics in a continuous process, comprising a tank adapted to contain dye liquor, a rotatable roll horizontally journalled within and spaced from the walls of said tank, means for torsionally vibrating and simultaneously rotating said roll, a plurality of rotatable pressure rolls in parallel alignment with said first mentioned roll, means for moving said pressure rolls toward said first mentioned roll comprising journal means supporting said pressure rolls, lever arm means supporting and secured to said journal means, and means pivotally supporting said lever arm means for movement of the pressure rolls to and away from said first mentioned roll, said means pivotally supporting said lever arm means having elements for adjustably securing said lever arm means in selected position for fixing the position of said pressure rolls with respect to said first mentioned roll.

4. A means for dyeing fabric in a continuous process comprising a tank adapted to contain dye liquor, a rotatable roll horizontally journalled in said tank, means for torsionally oscillating and simultaneously rotating said roll, two sets of pressure rolls parallel with said first mentioned roll, means for adjustably moving said sets of pressure rolls towards said first mentioned rolls comprising lever arm sections at the ends of each set of pressure rolls having journal means supporting the ends of said pressure rolls, lever arms at one end pivotally supporting said lever arm sections and having their other ends slidably and pivotally secured to said tank, and means for moving said pressure rolls into tangential contact with said first mentioned roll.

5. A means for dyeing fabric in a continuous process comprising a tank adapted to contain dye liquor, a rotatable torsionally vibratable roll horizontally positioned within and spaced from the walls of the tank, two pairs of squeeze rolls, means supporting one pair on one side of the rotatable torsionally vibratable roll, and means for supporting the other pair on the other side of the rotatable torsionally vibratable roll, and means for adjusting the pressure of each pair against said rotatable torsionally vibratable roll.

6. A means for dyeing fabrics in a continuous process comprising a tank adapted to contain dye liquor, a rotatable torsionally vibratable roll horizontally positioned in said tank and adapted to be immersed in a liquid, two pairs of squeeze rolls, lever arm means pivotally supporting independently each of said pair of rolls, and means for jointly operating said lever arms for exerting greater or less pressure against said rotatable torsionally vibratable rolls.

7. A means for dyeing fabrics in a continuous process comprising a tank adapted to contain dye liquor, a rotatable torsionally vibratable roll horizontally positioned within and spaced from the walls of the tank, two pairs of squeeze rolls, a lever arm for and supporting each squeeze roll for movement of said pairs of rolls into tangential contact with said rotatable roll, means for operating each of said pairs of squeeze rolls for exerting greater or less pressure of said squeeze rolls against said rotatable torsionally vibratable roll, comprising a pair of operating bars each pivotally engaging a pair of lever

arms with each connected near one end to the lever arm of one roll and intermediate its ends to a lever arm of the other roll of one pair, whereby said squeeze rolls may be pivotally moved toward said vibrating roll.

8. A fabric treating device comprising a supporting structure, a rotatable torsionally vibratable roll horizontally supported by said structure, means for simultaneously rotating and torsionally vibrating said roll, a pair of squeeze rolls tangentially arranged with respect to said rotating roll and with one of said squeeze rolls positioned above the axis of said rotating roll, and means for simultaneously adjusting said squeeze rolls away from or toward said rotating roll for controlling the tangential pressure between said rolls.

9. A device as set forth in claim 1 wherein said means for pressing comprises a lever arm pivotally supporting said additional rotating roll, and means for pivoting said lever arm whereby said additional roll is moved toward or away from said first-mentioned roll.

10. A fabric-treating device comprising a supporting structure, a rotatable torsionally vibratable roll horizontally supported by said structure, means for simultaneously rotating and torsionally vibrating said roll, a plurality of pairs of squeeze rolls parallelly positioned with respect to said rotatable roll, supporting arm means pivotally supported toward one end and journaling each pair of squeeze rolls thereby adapted to permit said squeeze rolls to swing toward and away from said rotatable roll, and means connected to said arms for causing said squeeze rolls to move toward and away from said rotatable roll.

11. A device as set forth in claim 7 wherein said last-mentioned means comprises a plurality of interconnected lever arms pivotally engaging said supporting arms and a common operating member for said interconnected lever arms for simultaneously moving said pairs of squeeze rolls.

12. A device as set forth in claim 7 wherein means are provided for adjustably and pivotally securing said one end of said supporting arm means in different positions whereby the normal pressure of said squeeze rolls against said rotatable roll may be changed.
